UNITED STATES PATENT OFFICE.

CHARLES L. WOODWARD, OF WEST SPRINGFIELD, MASSACHUSETTS, ASSIGNOR TO UNITED STATES MACHINERY MANUFACTURING COMPANY, OF SPRINGFIELD, MASSACHUSETTS, A CORPORATION OF MASSACHUSETTS.

DISHWASHING MACHINE.

Application filed March 10, 1922. Serial No. 542,674.

This invention relates to improvements in washing machines and particularly to machines for washing dishes in which a suitable inclosing casing or tank is provided for containing the dishes as knives, forks, spoons, cups, saucers, and plates while being washed. The lower portion of the dish receiving casing is designed to receive the hot water, and suitable means are provided for driving or forcing the hot water upward into contact with both the inner and outer surfaces of the articles to be washed, means are provided for operating a suitable propeller or other device for causing the water to be thrown upward, suitable means are also provided for preventing the water from collecting in the lower part of the receptacle so that the water is not churned around by the propeller without being thrown upward.

An object of the invention is to provide means for rotating the propeller by means of a water or other suitable motor which is located below the base or floor part of the dish receiving casing of the machine.

A further object is to provide a cover the shape of which is such that the water is readily deflected downward from the under side thereof and into contact with the outer surface of the articles being washed.

Further objects and nature of the invention will appear in the body of the specification and be particularly pointed out in the claims.

Referring to the drawings:—

Fig. 1 is a vertical sectional view through the axis of the propeller shaft and enclosing casing showing the interior construction thereof, the rack for supporting the dishes, the water deflector plates and the interior construction of the water motor.

Fig. 2 is a view showing the machine connected to the cold water faucet for operating the motor, and

Fig. 3 is a plan view substantially on the line 3—3 of Fig. 1 showing the concentric arrangement of the wires for supporting different articles as plates, tumblers, cups, etc., also the upper edges of the deflector plates which supports the dish receiving rack.

Referring to the drawings in detail:

1 designates the inclosing dish receiving casing or tank, which may be formed of any suitable sheet metal as copper. This casing

is provided with a removable cover 2 having the inwardly extending flange 3 which engages the bead 4. 5 designates the top plate or casting of the motor inclosing casing on which the bottom plate or portion 6 of the casing 1 rests. The plate 5 is formed with an integral upwardly extending tubular portion 7 in which is located the vertically arranged shaft 8 of the water motor, the buckets of the wheel of which are indicated at 9. These are of the well known Pelton water wheel type. These buckets are connected to the hub 10 which in turn is pinned to the shaft 8, as indicated at 11. 12 indicates the lower portion of the enclosing casing of the water motor and is formed with an upwardly extending member 13 which receives the lower end of the shaft 8. The outlet or discharging portion of the casing is indicated at 14. The upper end of the shaft 8 is provided with a suitable propeller blade 15 which is for the purpose of scooping and throwing the water upward as will be described. It is pinned to the shaft 8 as indicated at 16.

It is to be understood that only one propeller blade is to be used and is of such shape or form that the water is scooped up and thrown forcibly upwardly as indicated by the arrows 17 when the propeller is rotated. The proper water level in the casing 1 is indicated at 18. For the purpose of preventing the water from being churned around in a circle without being properly thrown upward a suitable number of deflector plates 19 are employed as shown. These plates are substantially right-angle triangles in form and are secured to the outer and lower edges of the casing 1. The upper edges 20 are designed for supporting the wire rack 21 which receives the dishes. This rack may be readily removed from the casing 1 when the cover 2 is removed permitting ready access to the interior. Located in the center part of the rack 21 is a woven wire fabric 22 that is rolled into a cylindrical shape for receiving the knives, forks, and spoons as indicated at 23.

Reference to the arrows will indicate the direction of the water as it is thrown upward at 17, and deflected downward as indicated at 24, whereby the inner and outer surfaces of the cups 25 and the tumblers 26 will be thoroughly washed also the inner and

outer surfaces of the plates which are indicated at 27. The arrows also show that the water is thrown upward into contact with the knives, forks and spoons in the wire receptacle 22. For the purpose of operating the motor a hose 28 is attached to the cold water faucet 20.

It is of course obvious that any other suitable motor may be utilized for operating 10 the propeller blade 15 as an electric, or steam motor.

It will be seen from this description that I have provided a simple and economical dish washing machine and one that can be 15 readily taken apart and repaired and thoroughly cleaned. The conical or inclined shaped surface of the cover 2 serves to cause the water which is thrown upward to be deflected or thrown downward again. The 20 single propeller blade 15 is driven by the water motor which is, as shown, attached to the shaft 8 between the bearing portions 7 and 13 of the enclosing water motor casing. The concentric wires 30 serve to receive 25 the edges of the plates 17.

It is to be understood that the propeller blade 15 is at all times only partially submerged as shown, which has the effect of scooping the water and throwing it forcibly 30 upward as shown by the arrows 17. This is an important feature.

What I claim is:

1. In a dish washing machine the combination of a cylindrical casing, a propeller 35 therein, a plurality of trapeziform deflector plates having the base portions thereof attached to the bottom portion of the casing and having the top portions thereof forming

supporting surfaces parallel to the bottom of the casing, a framework for holding 40 dishes having a portion of its flat bottom surface resting directly upon said supporting surfaces of said deflectors, the inner sides of said deflectors extending downwardly and inwardly towards the centre of the 45 bottom portion of the casing and defining with the bottom surface of said framework a clear space of inverted cone shape in which, said propeller is disposed, said propeller comprising a single shallow blade spaced 50 from the bottom of said casing and rotating in a plane parallel to the bottom surface of said framework and in close proximity to said framework, a cone shaped cover for said casing acting as a deflector for the water 55 thrown upwardly by said blade and means for operating said propeller.

2. In a dish washing machine the combination of a cylindrical casing, a propeller therein, a plurality of trapeziform deflector 60 plates having the base portions thereof attached to the bottom portion of the casing and having the top portions thereof forming supporting surfaces parallel to the bottom of the casing, a framework for holding 65 dishes having a portion of its flat bottom surface resting directly upon said supporting surfaces of said deflectors and the inner sides of said deflectors extending downwardly and inwardly towards the centre of the 70 bottom portion of the casing and defining with the bottom surface of said framework a clear space of inverted cone shape in which said propeller is disposed.

CHARLES L. WOODWARD.
